UNITED STATES PATENT OFFICE

WILLIAM B. WEEDEN, OF PROVIDENCE, RHODE ISLAND.

DESIGN FOR WOVEN FABRIC.

Specification forming part of Design No. 7,853, dated November 10, 1874; application filed September 5, 1874.
[Term of Patent 3½ years.]

CASE C.

To all whom it may concern:

Be it known that I, WILLIAM B. WEEDEN, of the city and county of Providence, in the State of Rhode Island, have invented a new Design for Fancy Cassimere Fabrics; and I do hereby declare that the following specification, taken in connection with the drawings making a part of the same, is a full, clear, and exact description thereof.

Referring to the drawings, A A represent stripes which run lengthwise of the fabric, and are woven in any preferred contrasting color or shading of colors. b b represent lines of "crape-cord" weaving arranged on both sides of the stripes A A, and from these

crape-cord lines spring cross-bars c c, arranged at regular intervals apart, the said lines b and bars c being placed upon a ground of plain weaving, and forming, in contrast with the narrow stripe A a broad ornamental stripe, B. The fabric may be made in any preferred variety or combination of colors for giving effect to the design above described.

What I claim as my invention is—

The design for cassimere fabrics as herein set forth, and represented in the drawings.

WILLIAM B. WEEDEN.
